Des. 218,068

Patented July 14, 1970

218,068

AUTOMOBILE WINDSHIELD SCRAPER

Sophia Stakis Psalidas, 24 N. Tacoma Ave.,
Tulsa, Okla. 74127

Filed Apr. 10, 1969, Ser. No. 16,663

Term of patent 14 years

Int. Cl. D7—06

U.S. Cl. D49—23

FIG. 4

FIG. 1

FIG. 2

FIG. 3

FIG. 5

FIG. 1 is a top plan view of an automobile windshield scraper showing my new design;

FIG. 2 is a side view thereof, the opposite side being a mirror image of the side illustrated;

FIG. 3 is a bottom plan view;

FIG. 4 is a view of one end;

FIG. 5 is a view of the other end.

I claim:

The ornamental design for an automobile windshield scraper, substantially as shown and described.
